UNITED STATES PATENT OFFICE

JOHN L. JONES, OF WEYMOUTH, MASSACHUSETTS, ASSIGNOR TO UNITED SHOE MANUFACTURING CORPORATION, OF PATERSON, NEW JERSEY, A CORPORATION OF NEW JERSEY

GAUGE MECHANISM FOR FASTENING INSERTING MACHINES

Application filed March 2, 1928, Serial No. 258,612, and in Great Britain December 24, 1927.

This invention relates to work-positioning means and is illustrated as embodied in a fastening inserting machine particularly adapted for use in repairing boots and shoes.

In repairing shoes, both soles and the top lifts of heels are often secured by wire staples inserted by the same machine. To secure a neat appearance of the work and to be properly effective, the fastenings which secure the sole of the shoe should be uniformly positioned at a suitable distance from the edge of the sole. As these soles are previously preliminarily attached to the shoes, for example by a few tacks, a gauge against which the edge of the sole bears is a satisfactory device. However, in securing top lifts, especially on wooden heels, it is customary to have the top lift somewhat larger than the heel and often rectangular or irregular pieces of stock are used for the purpose, these being trimmed to shape after they have been attached. Such being the case, it is necessary for the gauge that is used for this work to bear against the heel below the top lift and not against the top lift itself. Therefore, the gauge must be positioned in a lower plane, relatively to the nozzle or throat member of the machine, than the gauge that is used in attaching soles. Furthermore, in some other kinds of work, for example when inserting fastenings across the butts of half soles, the gauges previously referred to are not helpful and would be in the way.

It is, in view of the foregoing, an object of the present invention to solve these difficulties by providing improved gauge mechanism adapted to be used under the varying conditions met with in the repairing of boots and shoes.

Accordingly, a feature of the invention consists in a machine organization including a plurality of gauge members each of which is suitable for a different class of work, and which is so arranged that any one may be brought into operative position and locked against the usual pressures which are met with in machines of this type. As illustrated, these gauge members may readily be removed from operative position when no gauge is needed or another one needs to be substituted

for the one in use. This shifting of the gauge members may be done readily, according to this invention, without the use of tools.

It is desirable to vary the distance of the fastenings from the edge of the work in accordance with the character of the work. Accordingly, another feature of the invention consists in an arrangement of gauge members such that, when any one is in use, its position relative to the nozzle or throat member of the machine may be varied readily and the gauge held in adjusted position, also without the use of tools, the use of which would necessarily slow down the operator.

In the accompanying drawings,

Fig. 1 is a side elevation of a portion of a stapling machine embodying the invention with a gauge for use when attaching top lifts to heels in operative position and with a gauge for use when attaching soles indicated in inoperative position;

Fig. 2 is a similar side elevation of a portion of the machine with the position of the gauges interchanged, both gauges being shown in their entirety;

Fig. 3 is a front elevation of a portion of the machine, partly in section, with the top lift gauge in operative position and with the sole gauge in inoperative position;

Fig. 4 is a detail view of the gauge mechanism in front elevation with the sole gauge in operative position and the top lift gauge in inoperative position; and

Fig. 5 is a sectional detail view taken on the line 5—5 of Fig. 1, on a larger scale than Fig. 1.

The novel gauge is illustrated as embodied in a staple fastening inserting machine of the type disclosed in United States Letters Patent No. 1,016,930 granted upon an application of William H. Borden.

The main frame of the machine is illustrated at 10 and is provided with the usual wire feed rolls 12 by which the wire 14, from which the fastenings are formed, is supplied. The usual cutting knives are shown at 16 and 18 and the outside and inside formers are illustrated at 20 and 22 respectively. After the wire staple has been formed it is driven by the driver 24 through the driver passage

of the throat member or nozzle 26 into the work. These parts are fully illustrated and described in the above-mentioned Letters Patent, as are also the usual work receiving horn 28 and the horn tip 30 against which the fastenings are clenched.

The illustrated gauge mechanism is mounted upon a bifurcated member 32 which may be readily secured at its front end to existing machines by screws 34 while at the rear end it is clamped against the frame 10 of the machine by set screws 36 which are tapped into each of the arms 38 of the member 32.

The member 32 is provided with a T-slot 15 in which a slide 40 of T-shaped section is mounted (Fig. 5). To take up the wear of the slide 40, the member 32 is provided with a gib 42 held in position by set screws 44 and lock nuts 46. The slide 40 is provided on its upper surface with a toothed rack 48 by which it may be moved forwardly and backwardly through the engagement therewith of a pinion 50 mounted on a shaft 52. One end of this shaft is provided with an operating handle 54 and the other end with a friction washer 56, a friction spring 58 and friction adjusting nuts 60. The slide 40 has a downwardly projecting bracket 62 (Fig. 20 2) extending below the member 32. This bracket 62 is provided with a cross shaft 64 held in position by a set screw 66 (Figs. 3 and 4). On the shaft 64 are pivotally mounted a forepart gauge member 68 and a top lift gauge member 70. Each of these gauge members is provided adjacent to the shaft 64 with a slightly tapered rib 72 and the bracket 62 is provided, also adjacent to the shaft 64, with a correspondingly slightly tapered groove 74 on each side thereof. Each of the gauge members is provided with a double counter-bored hole 76 co-axial with that through which the shaft 64 passes. Located in the counter-bored hole of each gauge is a compression spring 78 mounted on the shaft 64. The outer end of this spring abuts on a washer 80 held on the outer threaded end of the shaft 64 by a nut 82. The outer ends of the bosses containing the counter-bores 76 are provided with hand grip knobs 84.

In order to bring either of the gauge members 68, 70 into operative position, that gauge member is lifted up from its depending position until it is substantially horizontal. When this position is reached, its spring 78 causes the gauge member to be moved towards the bracket 62, and the slightly tapered tongue 72 enters the correspondingly tapered groove 74, the spring moving the gauge axially of the shaft until the tongue and groove are in complete engagement. The slight taper of the tongue and groove brings the gauge member into proper vertical alignment with the nozzle 26. The tongue and groove

furnish a rigid support for the gauge against rotative downward or upward movement under pressure exerted by the shoe operated on, while the spring 78 is sufficiently strong to prevent any sidewise movement of the gauge. In order to bring either gauge into inoperative position, the reverse motions take place, to wit, the operator pulls on the knob 84 until the tongue and groove are disengaged and then swings the gauge downwardly out of the way so that the machine may be used without any gauge or the other gauge may be brought into operative position.

It will be noticed that the forepart gauge 68, as shown in Fig. 2, is positioned at a level such that the sole 86 being attached is positioned about midway of the height of the gauge surface. On the other hand, the top lift gauge 70, as shown in operative position in Fig. 1, is offset so that it is well below the top lift 88. The top lift is thus fastened at the desired fixed distance from the edge of the heel, which may be either wood or leather and, after being secured, it may be trimmed to fit the contour of the rest of the heel.

Attention is called to the fact that the gauge mechanism illustrated herein is of such a nature that it can be readily applied to outstanding machines without necessitating the use of machine-shop facilities.

Having described my invention, what I claim as new and desire to secure by Letters Patent is:

1. Gauge mechanism for controlling the presentation of shoes to the fastening instrumentalities of a fastening inserting machine comprising a gauge member formed and arranged to engage the edge of a sole to be attached to a shoe by fastenings inserted by the machine, a second gauge member formed and arranged to engage the heel of a shoe below its top lift when attaching a top lift to a heel; said gauge members being arranged so that either one of the two may be held positively in operative position while the other is positioned away from the work and is inoperative.

2. Gauge mechanism for controlling the presentation of work pieces to fastening inserting machines comprising a pair of gauge members mounted upon a shaft with respect to which either one of the gauge members may be swung from an inoperative to an operative position, a rib formed upon each gauge member, a member provided with slots arranged to receive the respective ribs of the gauge members, and a spring urging each gauge member toward the slotted member and yieldingly holding the rib of either of the gauge members in the corresponding slot when that gauge member is moved into operative position.

3. Gauge mechanism for controlling the presentation of work pieces to fastening inserting machines comprising a pair of gauge

members mounted upon a shaft with respect to which either one of the gauge members may be swung into operative position, a rib formed upon each gauge member adjacent to the shaft, a member adjacent to the shaft provided with slots arranged to receive the respective ribs of the gauge members, and a spring urging each gauge member toward the slotted member and yieldingly holding the rib of either of the gauge members in the corresponding slot when that gauge member is moved into operative position.

4. Gauge mechanism for controlling the presentation of work pieces to fastening inserting machines comprising a slide, a rack and pinion for moving the slide toward and from a work piece presented to the machine, friction means for holding the slide in adjusted position, a pair of gauge members carried by the slide and mounted for arcuate movement into and out of work-engaging position, one of said gauge members being formed and arranged when in operative position to engage the heel of a shoe presented to the machine at a level lower than the top lift of the heel and the other gauge member being formed and arranged when in operative position to engage the edge of the sole of a shoe presented to the machine, and means for positively holding either of the gauge members in operative position while the other gauge member is held out of operative position.

5. Gauge mechanism having, in combination, a plurality of gauge members, a shaft on which the gauge members are mounted for pivotal movement and for movement longitudinally of the shaft, and yielding means tending to move the gauge members along the shaft and arranged to hold each gauge member impositively when in inoperative position and to lock each gauge member against movement under the pressure exerted by a work piece when in operative position.

45 6. Gauge mechanism for positioning a shoe while operating upon its sole portions having, in combination, a plurality of gauge members, any one of which may be brought into operative position to locate a shoe relatively to the operating instrumentalities of a shoe-machine, a support for said gauge members, and locking means having parts integral with the support and said gauge members respectively for retaining one of the gauge members in operative position.

7. Gauge mechanism having, in combination, a plurality of gauge members, any one of which may be brought into operative position, a support for said gauge members, locking means having parts integral with the support and said gauge members for retaining one of the gauge members in operative position, and yielding means for rendering 65 the locking means either active or inactive.

8. Gauge mechanism having, in combination, a plurality of gauge members, a shaft on which the gauge members are mounted for pivotal movement and for movement longitudinally of the shaft, and a pair of 70 springs, one spring tending to move one of the gauge members along the shaft the other spring tending to move the other gauge member along the shaft, the springs being arranged to hold the gauge members impositively when in inoperative position and to lock the gauge members against movement under the pressure exerted by a work piece when in operative position.

9. Gauge mechanism for controlling the presentation of work pieces to fastening inserting machines comprising a shaft, a pair of gauge members mounted upon the shaft to permit either one of the two gauge members to be swung into operative position relatively to the fastening inserting instrumentalities of the machine or to permit both the gauge members to be swung into inoperative position, and means for locking in operative position either of the gauge members 85 that is swung to that position constructed and arranged positively to prevent downward movement of the operative gauge member.

In testimony whereof I have signed my name to this specification.

JOHN L. JONES.
